TAPE-APPLYING MACHINE

Walter P. Osgood, Malden, Mass., assignor to
 Boston Machine Works Company, Lynn, Mass.,
 a corporation of Massachusetts

Application December 30, 1932, Serial No. 649,497

16 Claims. (Cl. 12—51)

The present invention relates to machines which are used in the manufacture of shoes to apply tape to various portions of shoe upper parts such, for instance, as the flesh face of a single sheet or blank, and the seam-ridge formed in joining a plurality of sheets or blanks by a seam.

Generally, these tape-applying machines operate at a high speed to apply progressively to the work the free end portion of the tape extending in a continuous length from a source of supply in the machine. It has been proposed heretofore to provide these tape-applying machines with a tape-severing device operating, during the tape-applying operation, to sever the tape in advance of the point of operation, and thus provide the tape being applied to the work with a trailing edge. Heretofore the tape-severing device has been thrown into operation by the operative during the tape-applying operation. The operative observes the progress of the tape-applying operation and then throws the tape-severing device into operation to sever the tape in advance of the point of operation of the tape-applying mechanism to provide the tape with a trailing edge which, subsequently to being formed, is applied to the work during the continued operation of the tape-applying mechanism. But this trailing edge of the tape has an important relation to the rear edge of the work. In some kinds of work the trailing edge of the tape should be flush with the rear edge of the work. In other kinds of work the trailing edge of the tape should be either spaced from the rear edge of the work or projected therefrom. Stated in another way, it is highly desirable to be able to apply to the work a predetermined length of tape. Experience has demonstrated that it is impracticable to apply uniformly to successive work pieces a predetermined length of tape with a tape-applying machine in which the tape-severing device is thrown into operation by the operative.

The principal object of the present invention is to produce a tape-applying machine which will apply uniformly to successive work pieces a predetermined length of tape.

To the accomplishment of this object, a feature of the present invention contemplates the provision in a tape-applying machine provided with tape-applying and tape-severing mechanisms, of means for automatically initiating the throwing of the tape-severing mechanism into operation during the continued operation of the tape-applying mechanism.

Broadly considered the tape-severing mechanism may be thrown out of operation in any manner found desirable or expedient. Preferably, as the operative is subjected to the duty of inserting the work into the machine, the tape-severing mechanism is thrown out of operation by the operative during the act of inserting the work into the machine.

Accordingly another feature of the present invention contemplates the provision in a tape-applying machine provided with tape-applying and tape-severing mechanisms, and means under the control of the operative for throwing the tape-severing mechanism out of operation, of means for automatically throwing the tape-severing mechanism into operation.

Further features of the present invention reside in certain devices, combinations and arrangements of parts hereinafter described and then pointed out broadly and in detail in the appended claims, possessing advantages readily apparent to those skilled in the art.

The various features of the present invention will be readily understood from an inspection of the accompanying drawings illustrating the best form of the invention at present known to the inventor, in which,

Figure 1 is a detail view in left-side elevation of the tape-applying machine;

Fig. 2 is a detail view in front elevation, partly in section;

Fig. 3 is a view in sectional plan taken on the line 3—3, Fig. 1;

Fig. 4 is a detail view, partly in section, of the latch controlled by the end-feeler in latching position, taken on the line 4—4, Fig. 3;

Fig. 5 is a detail view in right-side elevation, partly in section, taken on the line 5—5, Fig. 2;

Fig. 6 is a detail view in left-side elevation showing the positions the parts assume during the tape-applying operation;

Fig. 7 is a view in perspective of the end-feeler, and

Fig. 8 is a view in perspective of the seam-ridge guide.

For convenience, the various features of the present invention are illustrated as embodied in a combined seam-pressing and taping machine of the type disclosed in my patents numbered 1,646,212 and 1,691,493 and dated October 18, 1927 and November 13, 1928, respectively. Accordingly, the work to which the tape is to be applied is illustrated as the seam-ridge 9 (Fig. 6) formed by joining a pair of shoe quarters 10 by a back seam 11. Those skilled in the art, how-

ever, will understand that, properly, the various features of the invention could have been illustrated as embodied in a top taping machine of the type disclosed in my patent numbered 1,549,376 and dated August 11, 1925.

The shoe quarters 18 (Fig. 6) are supported for the tape-applying operation by a roll 12 provided with a concave peripheral edge face 13. (Fig. 2). Associated with the roll 12 is a seam-crease guide 14. The seam-ridge 8 is guided by a guide (Figs. 1, 2, 5, 6, and 8) provided with rearwardly extending arms 15 which embrace the opposite sides of the upstanding seam-ridge 8. The seam-ridge guide is secured by a screw 16 to an arm 17 (Fig. 1) supported from a bracket 18. The bracket 18 is secured to a block 19 which is supported by a bracket 200 secured to the machine frame.

After the work has been placed in position on the roll 12 with the seam-crease and the seam-ridge engaged by their respective guides, the tape is applied to the work by a seam-pressing member 20 carried by a lever or head 21. The head 21 is formed with a slot 22 (Fig. 1) in which is received a block 23 that is pivoted at 24 to the machine frame. The upper end of the head 21 is connected to an eccentric (not shown) on the drive shaft 25. As disclosed more fully in my Patent No. 1,646,212 this construction reciprocates the member 20 to press the seam-ridge and apply tape thereto and oscillates the pressing member in contact with the work to impart thereto a feeding movement. During this feeding movement the pressing-member 20 draws tape through a tape-guide 26 from a suitable source of supply extending in the machine from a coil (not shown) to the tape-guide. Intermediate the coil and the tape-guide the machine is provided with a tape pull-off mechanism having substantially the same construction and mode of operation as the corresponding pull-off disclosed in my Patent No. 1,899,051, February 28, 1933.

The tape-guide comprises a narrow bar 27 (Fig. 3) having its opposite ends turned up to form a guide way for the passage of the tape. The tape is pressed against the bar 27 by a clamping-plate 28 which is provided with ears 29 (Figs. 1 and 6) which receive a horizontal pin 290 carried by ears 30 formed on a plate 31. The clamping plate 28 is held in engagement with the tape by a light spring 32 coiled about the pin 290, one end of the spring being engaged with the tail of the plate 28 and the other end of the spring 32 being engaged with the plate 31. The plate 31 is supported by a bar 33. The bars 27 and 33 are carried by an arm 34 secured to one end of a rock-shaft 35 (Figs. 5 and 6) journaled in the block 19. The other end of the rock-shaft 35 is provided with an arm 36. The rear end of the arm 36 is connected by a coiled spring 37 to the machine frame. Thus the tape-guide is held by the spring 37 normally in the position of Fig. 1 with its tape delivery end above the path of movement of a tape-severing knife 38.

The tape-severing knife 38 comprises a plate 39 (Fig. 3) provided with a salient cutting edge 40. The plate 39 is secured to a holder 41 projecting laterally from one end of an arm 42 the other end of which is secured to one end of a rock-shaft 43 journaled in the block 19. The other end of the rock-shaft 43 is provided with a cam-plate 44 which, when the parts are in the position shown in Fig. 1, is engaged by a button 45 rotatably mounted on one end of a horizontal rod 46 slidably mounted in the reciprocating and

oscillating head 21. The button 45 is maintained at one side of the vertical plane of the cam-plate 44 by a leaf spring 47 one end of which is secured to the head 21 and the other end of which is forked to embrace the rod 46 and engage the button 45 and move it and the rod 46 to the right (Fig. 3) until stopped by a cotter pin 48 (Fig. 1) on the opposite end of the rod 46. The button 45 is pressed to the left (Fig. 3) against the tension of the spring 47 by a cam-plate 49 (Figs. 2 and 3) formed on one end of a lever 50 (Fig. 5) pivoted on the rock-shaft 35. The other end of the lever 50 is connected to the bracket 200 by a coiled spring 51 much lighter than the spring 37. With this construction the spring 51 tends to withdraw the cam-plate 44 from the button 45 to restore it to the influence of the spring 47.

In order to rock the lever 50 in a direction to engage the cam-plate 49 with the button 45 and thus press it to the left against the tension of the spring 47, the lever 50 is provided with a lateral pin 52 (Fig. 5) which is normally engaged by the upper edge of the arm 36 under the influence of the heavy spring 37. The movement of the arm 36 and the lever 50 as a unit under the influence of the heavy spring 37 is limited by a stop pin 53 projecting laterally from the block 19 in a position to engage the upper edge of the lever 50. The movement of the lever 50 separately, to be described, under the influence of the light spring 51 is limited by a stop pin 54 projecting laterally from the block 19.

Thus, through the connections described the button 45, while subject to the influence of the springs 47 and 51, is maintained normally in the vertical plane of the cam-plate 44 by the heavy spring 37 so that the cutter 38 is operated to sever the tape by the same power-driven mechanism which reciprocates and oscillates the seam-pressing and tape-applying member 20. The cutter 38 is actuated to sever the tape on one of the downward movements of the head 21. The cutter 38 is retracted after its tape-severing movement by a coiled spring 55 (Figs. 1 and 6) one end of which is connected to the block 19 and the other end of which is connected to an extension 56 on the arm 42, a slabbed-off pin 57 limiting the movement of the cutter 38 under the influence of the spring 55.

In order to facilitate the application of the free end of the tape dangling from the delivery end of the tape-guide after the tape-severing operation, the tape, just below the delivery end of the tape-guide, is engaged by one end of a plate 58 (Figs. 1 and 6) the other end of which is pivoted 55 on a pin 59 (Fig. 3) projecting laterally from the block 19. The plate 58, near its tape engaging end, is pressed yieldingly against the bottom of the bar 27 by a spring 60 (Fig. 3) coiled about the pin 59, one end of the spring being connected to the pin 59 and the other end of the spring being engaged with the bottom of the plate 58.

The plate 58 constitutes an auxiliary tape-guide which, because it is pivoted on a different axis than the main tape-guide, is projected beyond the delivery end of the main tape-guide when it is located in the tape-applying position (Fig. 6) and thus deposits the free end of the tape upon the work in position to be engaged by the pressing member 20. During the tape-severing operation the pressure exerted by the tape-severing knife on the tape presses the sticky face thereof against the bar 27. The plate 58 constitutes also a stripper for stripping the tape from the bar 27.

In order to rotate the rock-shaft 35 and thus rock the tape-guide below the path of movement of the cutter 38 into the position of Fig. 6, where the leading edge of the tape is deposited upon the work by the auxiliary tape-guide, the rear end of the arm 36 (Fig. 5) is connected by a link 61 to one end of a lever 62 pivoted on the machine frame. The other end of the lever 62 is provided with a cam surface 63 which is engaged by a roll 64 carried by the lower end of an arm 65 (Fig. 2) secured to a rock-shaft 66 journaled in the machine frame. The other end of the rock-shaft 66 is suitably connected to a treadle rod 67.

When the treadle-rod 67 is depressed to move the tape-guide from the position it occupies during the tape-severing operation to the position it occupies during the tape-applying operation, the lever 50 is restored to the influence of the spring 51. In order to positively separate the cam-plate 49 from the button 45, the right hand face of the lever 50 is provided with a screw 68 (Fig. 5) the shank of which rides in a blind slot 69 formed in a link 70 pivoted to the lever 62. With this construction depression of the treadle-rod causes the blind end of the slot 69 to engage the shank of the screw 68 to positively initiate the separation of the cam-plate 49 from the button 45 thus to insure the restoration of the lever 50 to the influence of the spring 51. When the cam-plate 49 is withdrawn completely away from the button 45 by the spring 51, the spring 47 moves the button out of the vertical plane of the cam-plate 44 thus throwing the tape-severing knife 38 out of operation.

In order to retain the tape-guide in the tape-applying position and the tape-severing knife out of operation during a part, at least, of the tape-applying operation, the front end of the arm 36 is provided with an L-shaped hardened steel plate 71 (Figs. 3, 4 and 5) arranged to be supported by a latch 72 only when work is in the machine and the treadle-rod 67 has been depressed. The latch 72 is secured to one end of an arm 73 the hub of which is formed as a clamp 74 to embrace and to be secured adjustably to a horizontal rock-shaft 75 journaled in the bracket 18. The front edge of the arm 73 is engaged by the point of a screw 76 carried by an arm 77 secured to one end of the rock-shaft 75. The other end of the rock-shaft 75 is provided with a screw 78 (Figs. 1 and 2) having a slabbed-off portion which embraces the longitudinal edges of a slot 79 formed in a plate 80, there being a washer interposed between the plate 80 and the head of the screw 78 to facilitate the clamping of the plate 80 in its desired position of adjustment relative to the axis of the rock-shaft 75. Connected to the sides of the plate 80 is a pair of plates 81 the rear ends of which embrace the peripheral edge of the seam-crease guide 14 when no work is in the machine. The front edges of the plates 81 flare laterally to act as a guide in inserting the seam-ridge into the machine. When no work is in the machine the plates 80 and 81 are held in the position of Fig. 1 by a spring 82 (Figs. 2, 3 and 4) coiled about the rock-shaft 75 one end of the spring 82 being engaged with the bracket 18 and the other end of the spring being engaged with a collar 83 secured to the rock-shaft 75.

With this construction the operative depresses the treadle-rod 67 thereby throwing the tape-severing knife 38 out of operation, lowering the 75 tape-guide into its tape-applying position, and

elevating the plate 71 on the front end of the arm 36. At the same time the operative starts to insert the work into the machine between the seam-crease guide 14 and the ends of the plates 80 and 81 engaged thereby. The work elevates the plates 80 and 81 which ride on the end edge face of the seam-ridge and embrace the seam-ridge, respectively, thereby rocking the rock-shaft in a clockwise direction (Figs. 1 and 2) and elevating the latch 72 into a position where it 10 engages under and latches the plate 71 in its elevated position. The free end of the plate 80 rides on the seam-ridge during the tape-applying operation until the end of the seam-ridge is reached when the plate 80 drops off the end of 15 the work thus tripping the latch 72 to allow the heavy spring 37 to rock the tape-guide upwardly above the path of movement of the tape-severing knife 38 and to throw it into operation. Hereinafter the plate or plates engaged with the work 20 during the tape-applying operation is or are designated as "an end-feeler".

By adjusting the position of the end-feeler relative to the axis of the rock-shaft 75, by varying the position of the arm 73 relative to the circumference of the rock-shaft, and by adjusting the position of the screw 76 relative to the adjusted position of the arm 73, the end-feeler may determine the time at which the tape-severing knife is thrown into operation to produce a trailing edge for the tape being applied to the work so that it will be projected beyond the end of the work, be flush with said end or spaced therefrom. Stated in another way, the end-feeler determines automatically the distance of the end of the work 35 from the point of operation and throws the tape-severing knife into operation when the end of the work reaches a predetermined distance from said point of operation.

Nothing herein explained is to be interpreted 40 as limiting the various features of the present invention in the scope of its application to use in connection with the particular machine or the particular mode of operation or both selected for purposes of illustration and explanation. 45 While the particulars of construction herein set forth are well suited to one mechanical form of the invention and to the use to which it is put, it is not limited to this use, nor to these details of construction, nor to the conjoint use of all its 50 features, nor is it to be understood that these particulars are essential since they may be modified within the skill of the artisan without departing from the true scope of the actual invention, characterizing features of which are set forth in 55 the following claims by the intentional use of generic terms and expressions inclusive of various modifications.

What is claimed as new, is:

1. A tape-applying machine having, in combination, tape-applying and tape-severing mechanisms, and automatic means controlled by the size of the work for initiating the throwing of the tape-severing mechanism into operation during the continued operation of the tape-applying 60 mechanism.

2. A tape-applying machine having, in combination, tape-applying mechanism, tape-severing mechanism, means under the control of the operative for throwing the tape-severing mechanism out of operation, and mechanism for automatically throwing the tape-severing mechanism into operation.

3. A tape-applying machine having, in combination, tape-applying mechanism, tape-sever- 75

- ing mechanism, means under the control of the operative for throwing the tape-severing mechanism out of operation and mechanism, rendered active in inserting the work into the machine, for 5 retaining the tape-severing mechanism out of operation and for automatically throwing the tape-severing mechanism into operation.
4. A tape-applying machine having, in combination, tape-applying mechanism, tape-severing mechanism, and automatic means controlled by the size of the work for throwing the tape-severing mechanism into operation during the continued operation of the tape-applying mechanism.
- 10 5. A tape-applying machine having, in combination, tape-applying mechanism, a tape-severing device, and means arranged to engage the work and be controlled thereby to automatically throw the tape-severing device into operation when the end of the work reaches a predetermined 20 distance from the point of operation of the tape-applying mechanism.
- 25 6. A tape-applying machine having, in combination, tape-applying mechanism, a tape-severing device, an end-feeler arranged to ride on the work in advance of the point of operation of the tape-applying mechanism, and mechanism controlled by the end-feeler and operating, when said feeler drops off the end of the work, to throw the 30 tape-severing device into operation.
- 35 7. A tape-applying machine having, in combination, tape-applying means, power-driven mechanism for operating the tape-applying means, a tape-severing device normally connected to the power-driven mechanism, a tape-guide normally occupying a position above the path of operation of the tape-severing device, means under the control of the operative for disconnecting the tape-severing device from the power- 40 driven mechanism and for locating the tape-guide below the path of movement of the tape-severing device in position to deliver the tape to the work, and means operating automatically for restoring the tape-guide to its normal position and for reconnecting the tape-severing device to the power-driven mechanism.
- 45 8. A tape-applying machine having, in combination, a continuously operating tape-applying mechanism, an intermittently operating tape-severing mechanism, and automatic means for determining the time of operation of the tape-severing mechanism.
- 50 9. A tape-applying machine having, in combination, tape-applying and tape-severing mechanisms, a tape-guide cooperating in one position with the tape-applying mechanism and in another position with the tape-severing mechanism, and automatic means for moving the tape-guide from the position in which it cooperates with the tape-applying mechanism to the posi- 55 tion in which it cooperates with the tape-severing mechanism.
5. A combined seam-pressing and taping machine having, in combination, tape-applying mechanism, a tape-severing device, a movable seam-ridge guide, and mechanism controlled by the movable seam-ridge guide and operating when it drops off the end of the seam-ridge to throw the tape-severing device into operation.
- 10 6. A combined seam-pressing and taping machine having, in combination, tape-applying mechanism, a tape-severing device, a stationary seam-ridge guide, a movable seam-ridge guide, and mechanism controlled by the movable seam-ridge guide and operating when it drops off the end of the seam-ridge to throw the tape-severing device into operation.
- 15 7. In a tape-applying machine, the combination with a main tape-guide mounted on one axis, of an auxiliary tape-guide mounted on another axis and arranged to engage the main tape-guide.
- 20 8. A tape-applying machine having, in combination, tape-applying and tape-severing mechanisms, a tape-guide cooperating in one position with the tape-applying mechanism and in another position with the tape-severing mechanism, and automatic means for moving the tape-guide from the position in which it cooperates with the tape-applying mechanism to the position in which it cooperates with the tape-severing mechanism and for throwing the tape-severing device into operation.
- 25 9. A tape-applying machine having, in combination, means for supporting a continuous length of tape, and mechanism controlled by the size of the work, thrown into action automatically for cutting a predetermined length of tape from the free end portion of the continuous length of tape.
- 30 10. A tape-applying machine having, in combination, means for supporting a continuous length of tape, mechanism, controlled by the size of the work, thrown into action automatically for cutting a predetermined length of tape from the free end portion of the continuous length of tape, and mechanism for applying the predetermined length of tape to the work.
- 35 11. A tape-applying machine having, in combination, means including a guide for supporting a continuous length of tape, tape-applying and tape-severing mechanisms, mechanism thrown into action automatically for elevating the guide and for cutting a predetermined length of tape from the free end portion of the continuous length of tape, and mechanism for lowering the guide to deposit the free end of the continuous length of tape upon the work in position to be engaged by the tape-applying mechanism.

WALTER P. OSGOOD.
